(57) **CLAIM**

The ornamental design for a ski leg, as shown and described.

DESCRIPTION

FIG. 1 is a perspective illustration, from the front and left side, of a first embodiment of the ski leg of our design; FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a bottom view thereof;

FIG. 8 is a perspective illustration, from the front and left side, of a second embodiment of the ski leg of our design; FIG. 9 is a left side view thereof;

FIG. 10 is a right side view thereof;

FIG. 11 is a front view thereof;

FIG. 12 is a rear view thereof;

FIG. 13 is a top view thereof; and,

FIG. 14 is a bottom view thereof.

Where included, broken lines showing structure are for illustrative purposes only and form no part of the claimed design.
